(57) **CLAIM**

The ornamental design for a car wash entry station face plate, as shown and described.

DESCRIPTION

FIG. 1 is a perspective view of a car wash entry station face plate embodying the present invention;

FIG. 2 is a top view of the car wash entry station face plate;
FIG. 3 is a bottom view of the car wash entry station face plate;

FIG. 4 is a front view of the car wash entry station face plate;

FIG. 5 is a left side view of the car wash entry station face plate; and,

FIG. 6 is a right side view of the car wash entry station face plate.

The broken lines in the drawings depict environmental structure, which forms no part of the claimed design.
